(57) **CLAIM**

I claim the ornamental design for a multi-use canopy.

DESCRIPTION

FIG. 1 is a front elevated view of my new design for a multi-use canopy, thereof;

FIG. 2 is a front perspective view, thereof;

FIG. 3 is a left side elevated view wherein the right side is a mirror image, thereof;

FIG. 4 is a rear elevated view, thereof;

FIG. 5 is a top plan view, thereof;

FIG. 6 is a bottom plan view, thereof;

FIG. 7 is a right side elevated view shown in a usable position, thereof; and,

FIG. 8 is a front elevated view shown in a position of use. In the drawings, the broken lines in FIG. 7 depict portions of the article that form no part of the claimed design.

The crosshatching in the drawings represent the webbing material used in the design. The elongated broken lines on the surface areas of the multi-use canopy represent the stitching used in the design. The mobility chair, mobility scooter accessory, motor scooter and adjustable scooter apparatus shown in broken lines in FIGS. 7 and 8 are included for the purpose of showing the multi-use canopy in use and form no part of the claimed design.
